UNITED STATES PATENT OFFICE.

LOUIS A. BAUMANN, OF WHEELING, WEST VIRGINIA.

FLOOR-DRESSER.

SPECIFICATION forming part of Letters Patent No. 619,464, dated February 14, 1899.

Application filed March 21, 1898. Serial No. 674,627. (No model.)

To all whom it may concern:

Be it known that I, LOUIS A. BAUMANN, a citizen of the United States of America, and a resident of Wheeling, county of Ohio, State 5 of West Virginia, have invented certain new and useful Improvements in Floor-Dressers, of which the following is a specification.

This invention relates to certain new and useful improvements in floor-dressers, and 10 has for its object to construct a device whereby by an even and smooth surface on a floor may be accomplished.

A further object of my invention is to construct a device that may be moved over the 15 surface of the floor in any desired direction and may be adjusted to any position near to or away from the floor.

In describing the invention in detail reference is had to the accompanying drawings, 20 forming a part of this specification, wherein like figures of reference indicate similar parts throughout the several views, in which—

Figure 1 is a perspective view of my improved floor-dresser. Fig. 2 is a detached 25 view of the cutter-head. Fig. 3 is a top plan view of a head for holding sandpaper. Fig. 4 is a bottom plan view of the same. Fig. 5 is a sectional view on line $\alpha\alpha$, Fig. 2.

Referring to the drawings, 1 designates the 30 frame, which is substantially triangular in shape and is provided with rollers 2 of any ordinary form.

3 and 4 are triangular-shaped frames which are held in position by screw-threaded rods 35 5, engaging screw-threaded openings formed in the frames 3 and 4, said screw-threaded rods 5 serving to regulate and adjust the cutter-head 6 with relation to the floor, said cutter-head being provided with a series of bits or 40 blades 7, which are secured in the openings 8, formed in the cutter-head. Said cutter-head is secured to a shaft 9, which is journaled in the frames 3 and 4. Mounted on said shaft 9 is a pulley 10. Secured in said frames 3 and 45 4 and near the base thereof are braces 11 and 12. Journaled in said braces is a shaft 13, carrying a bevel gear-wheel 14 and a pulley 15. Journaled in the brace 12 and the base of frame 4 is a shaft 16, carrying on one end 50 an operating-handle 17. Secured to said shaft 16, between the brace 12 and the base of the

frame 4, is a fly-wheel 18. Said shaft 16 carries on its inner end a bevel-gear 19, meshing with the bevel-gear 14, secured to the shaft 13. Engaging the pulleys 10 and 15 is an endless 55 belt 20. Secured to the frame 3 are hooks 21, of any desired shape, to which are secured stay-wires 22. The opposite end of said stay-wires are secured to a similar hook 23, carried by the frame 4, said stay-wires serving to 60 prevent lateral motion of the frame.

In Figs. 3 and 4 I have shown a modified head to which sandpaper is secured, whereby a smooth surface is given to the floor, and it consists of a disk 24, provided on its top face 65 with a projecting flange 25, adapted to be secured to the shaft 9. Engaging the periphery of said disk is a split ring 26, and between which and the periphery of the disk 24 the sandpaper is adapted to be secured. Said 70 split ring is secured in position by means of a bolt 27, passing through a lug formed on the ends of said ring.

The operation of the device is apparent 75 from the drawings and the description.

It will be noted that various changes may be made in the details of construction without departing from the spirit of my invention.

What I claim, and desire to secure by Letters Patent, is—

In a device of the character described, a base-frame, a second frame having its end extending beyond the end of the base-frame, a frame above and corresponding with the second frame, brace-wires between the two upper frames, a shaft mounted in the ends of the two upper frames and depending therefrom in front of the base-frame, a cutter-head on the shaft, cranked rods threaded in apertures of the upper and mounted in the base-frame, rollers on the ends of the rods, said rods being adapted to hold the frames in the same relative position while the base-frame is being adjusted with relation to the floor and means for driving the shaft, as and for 95 the purpose described.

Signed by me, at Wheeling, West Virginia, this 8th day of March, 1898.

LOUIS A. BAUMANN.
